COMBINATION DUMBBELL AND INDIAN CLUB

Nathan L. Paves, New York, N. Y.

Application April 27, 1939, Serial No. 270,271

4 Claims. (CL. 272—84)

This invention relates to implements used in performing physical exercises, particularly in developing the muscles of the arms, back and hands to a high degree of efficiency.

5. In gymnasias the more common appliances are Indian clubs and dumbbells, which the habitues are taught to handle scientifically and trained in many maneuvers, tending to promote good health, increase strength, inculcate gracefulness 10 in action, and generally acquire poise in movement of a highly desirable nature.

In the home, where room is restricted, the paraphernalia is necessarily limited in scope, and the expense usually is also considered.

15. Having these matters in mind, and fully recognizing the valuable effect of even moderate exercise, it is an object of this invention to provide a simple appliance combining the characteristics of a club and dumbbell, so arranged 20 that it can be metamorphosed into condition for use in either form.

A further feature is in the provision of an appliance suited for service by persons of either sex and varying in age and physique, who seek 25 to secure the advantages derived by proper exercise, although possibly constrained to home practice.

Another purpose is to produce an implement of 30 inexpensive construction, admirable appearance, and capable of being changed to operate either as an Indian club or dumbbell, easily, quickly, and without the use of tools or extraneous means.

These meritorious aims are accomplished by 35 the novel construction and arrangement of few and simple parts, hereinafter described and illustrated in the accompanying drawing, constituting an important part of this disclosure, and in which:

Figure 1 is a front elevational view of an embodiment of the invention assembled to represent a conventional Indian club.

Figure 2 is a central longitudinal sectional view of the same.

Figure 3 is a sectional detail view of a removable shank handle having a rod wrench enclosed therein.

Figure 4 is a view of an insertible bar by which the weight of the device may be increased.

Figure 5 is a fragmentary sectional view showing a method of locking the shank handle to the body of the device.

Figure 6 is a plan view of the locking member.

Figure 7 is a fragmentary sectional view showing a modified form of securing the central tube 5 in the club head before being locked therein.

Figure 8 is a view similar to Figure 7, showing the tube securely locked to the head.

Reference to the drawing will show a main body, generally designated by the numeral 15, of circular cross section throughout, as having 5 a head 16, preferably concave at its extremity 17 and of elliptical configuration.

An annular recess 18, in its largest diametered portion 16, has set in it a cushion ring 19, as rubber, to dull the sound of striking objects, 10 and for the further purpose of avoiding injury to them.

A swelled handle portion 20, integrally connected by a reduced neck 21 to the head, is similarly reduced, as at the neck 22, and blending 15 into an enlarged end 23, so shaped and proportioned as to substantially equal the weight of the head 16, when the handle 20 is grasped.

These unitary elements contain an axial bore 24 in which is secured a tubular sleeve 25, its 20 inner end 26 corrugated or threaded to become permanently fixed in the head 16, these elements constituting, in effect, a dumbbell.

When desired to use the device as an Indian club, an auxiliary handle 30 is joined to the 25 element 23 as a continuation thereof, the handle 30 having a spherical knob 31 at its outer end.

Fixed in the knob, prior to its being rigidly fastened on the handle end 30, is a bushing 32, 30 interiorly threaded to receive the correspond- ing end of a rod or clamp bolt 34, having an enlargement or head 35 at its opposite, inner end and provided with screw threads 36 to engage within the threads 27 of the sleeve 25, thereby to firmly unite the handle 30 to the elements of the dumbbell, the effect being to produce a form of Indian club.

If more weight is desired, a bar 40 of metal, as lead, iron, etc., may be inserted into the sleeve 25 and held by its screw threads 41, which are 40 fitted to engage the threads 27 in the sleeve.

In order to insert and lock the bar 40, its outer terminal 42 is flattened and engageable by a fork 43, formed in the enlarged end 35 of the combination bolt and wrench 34. Obviously the bar 40 may be retracted by reverse manipulation of the element 34.

To avoid unintentional relative rotation of the handle 30 and body 15, a recess 45 is formed in the element 23 and pivoted in the recess, as by a 50 pin 46, is a detent lever 47, its longer arm 48 engageable in a groove 49 in the handle 34, and is normally held therein by virtue of a spring 50.

One end of the spring 50 is set in an indentation 52 in the bottom of the recess 45, to im- 55

pinge against the broadened, opposite end 51 of the detent lever, a boss 53 being provided on the lever to retain the spring in operative position. Obviously, when the end of the lever, at at 51, is pressed inwardly, it releases the arm 48, permitting relative rotary motion of the handle and body as indicated in dash dot lines in Figure 5.

Referring to Figures 7 and 8 showing a modified form of securing the sleeve 25 within the bore 24. It is obviously very essential to retain the sleeve 25 securely within the upper portion of the club 15 to prevent the accidental disengagement of the club from the handle 34 attached to the tube 25 while the club is being swung or otherwise being used for exercising.

This is accomplished by forming a plurality of tongues 60 in the end 61 of the sleeve 25. These tongues are preferably formed with hook-like elements 62 and are pressed inwardly, as shown in Figure 7 when the sleeve 25 is inserted into the opening 24. After the sleeve has been located in its proper place within the opening 24, a plunger type tool 63 is inserted in the sleeve 25, and forced against the inwardly bent tongue 60, thereby spreading the tongues and forcing their hook-like elements 62 into the wall of the bore 24, in the head 16, thus securely locking the sleeve 25 within the club member 15.

It is to be understood that all parts are suitably finished and when assembled present smooth surfaces, the detent lever elements being flush and level with the surfaces in which they are set.

From the foregoing it will be seen that an effective, double purpose, exercising appliance has been disclosed in the preferred form of its embodiment, but it is to be understood that changes may be made in form, proportions and in such minor details as may come within the scope of the appended claims.

Having thus described the invention, including its construction and operation, what is claimed as new and sought to secure by Letters Patent is:

1. A convertible exercising implement comprising a dumbbell having an annular groove in one of its end elements, a cushion ring set therein, a metal sleeve fixed axially in said dumbbell, said

sleeve open at the end opposite the grooved element, a heavy bar disposed in said sleeve, an auxiliary handle, and a bolt fixed in said handle to removably engage said sleeve.

2. A convertible exercising implement comprising a dumbbell having an annular groove in its periphery at one end, a cushion ring set therein, a metal sleeve fixed axially in said dumbbell, said sleeve open at the end opposite the grooved end, and having an internal thread, an auxiliary handle, a knob combined therewith, a bolt fixed in said knob to extend axially through said handle, a head on said bolt threaded to engage in said sleeve, and detent means to prevent rotation of said handle and bolt relative to said dumbbell, said detent means being manually retractable.

3. A convertible exercising implement comprising a dumbbell having an annular groove in its periphery at one end, a cushion ring set therein, a metal sleeve fixed axially in said dumbbell, said sleeve open at the end opposite the grooved end, and having an internal thread, a weight bar engageable in said sleeve, an auxiliary handle having a knob at one end, a bolt fixed in said knob reaching through said handle, a head on said bolt to engage the threads of said sleeve whereby to rigidly secure the handle on the end of the dumbbell, and means in said bolt head to engage and release said weight bar.

4. A convertible exercising implement comprising a dumbbell having an annular groove in its periphery at one end, a cushion ring set therein, a metal sleeve fixed axially in said dumbbell, said sleeve open at the end opposite the grooved end, and having an internal thread, a weight bar engageable in said sleeve, and the threads therein, a flattened terminal on said bar, an auxiliary handle having a knob at its outer end, a clamp bolt fixed in said knob to extend axially through the handle, an enlarged head in said bolt threaded to engage the threads of said sleeve, a fork on the threaded end of said head to engage the terminal of said weight bar, and manually releasable means to lock said handle to said dumbbell.

NATHAN L. PAVES.
